JP 681836 U 11/1994
WO 0030893 A1 6/2000

Primary Examiner — Katrina A Betton*(74) Attorney, Agent, or Firm* — Price Heneveld LLP;
Bradley D. Johnson(57) **CLAIM**

I claim the ornamental design for a rearview assembly, as shown and described.

DESCRIPTION

FIG. 1 is a front perspective view of a rearview assembly of the present disclosure;

FIG. 2 is a rear perspective view of the rearview assembly of FIG. 1;

FIG. 3 is a front elevational view of the rearview assembly of FIG. 1;

FIG. 4 is a rear elevational view of the rearview assembly of FIG. 1;

FIG. 5 is a first side elevational view of the rearview assembly of FIG. 1;

FIG. 6 is a second side elevational view of the rearview assembly of FIG. 1;

FIG. 7 is a top plan view of the rearview assembly of FIG. 1; and,

FIG. 8 is a bottom plan view of the rearview assembly of FIG. 1.

Broken lines are environmental only and form no part of the claimed design.
